US0D1053172S

(12) **United States Design Patent** (10) Patent No.: **US D1,053,172 S**
(45) Date of Patent: ** Dec. 3, 2024

(54) **EARPHONE COVER**

(71) Applicant: **Yi Chai**, Edinburgh (GB)

(72) Inventor: **Yi Chai**, Edinburgh (GB)

(**) Term: **15 Years**

(21) Appl. No.: **29/947,479**

(22) Filed: **Jun. 14, 2024**

(30) **Foreign Application Priority Data**

Feb. 6, 2024 (CN) 202430081708.9

(51) **LOC (14) Cl.** **14-01**

(52) **U.S. Cl.**

USPC **D14/223**

(58) **Field of Classification Search**
